UNITED STATES PATENT OFFICE.

MARK LANE MILFORD, OF LINDEN HEIGHTS, OHIO.

HEATING-STOVE.

1,178,867.

Specification of Letters Patent. Patented Apr. 11, 1916.

Application filed February 7, 1916. Serial No. 76,620.

To all whom it may concern:

Be it known that I, MARK L. MILFORD, a citizen of the United States, residing at Linden Heights, in the county of Franklin and State of Ohio, have invented certain new and useful Improvements in Heating-Stoves, of which the following is a specification, reference being had therein to the accompanying drawing.

10 This invention relates to improvements in heating stoves, and particularly to a novel construction and arrangement of grates for coal burning stoves, the primary object of the invention being to provide a novel construction and disposition of the grate within the stove body, by means of which the more thorough and efficient oxygenation of the fuel and gases is secured and better combustion obtained, with the generation of a 20 higher degree and amount of heat and increased economy in the use of fuel.

A further object of the invention is to provide a construction and arrangement of grate in connection with the casing walls 25 and draft door of a stove, by means of which air will be supplied to all portions of the fuel and generated gases, the heat thrown off at a lower elevation for radiation, the walls and surfaces of the stove bet- 30 ter protected against excessive heating through contact with the hot fuel, and greater ease afforded in shaking the grate and keeping it clear of ashes and clinkers.

With these and other objects in view the invention consists in the features of construction, and the combination and arrangement of parts hereinafter described, reference being had to the accompanying drawings, in which:

40 Figure 1 is a front elevation of a heating stove constructed in accordance with my invention; Fig. 2 is a horizontal transverse section through the same; Fig. 3 is a vertical front to rear section through the stove; 45 and Fig. 4 is a detail vertical section through one side of the fuel basket and grate, and showing one of the supporting brackets.

Referring to the drawings, 1 designates the body, drum or casing of the stove, which is preferably in the form of a vertically disposed cylinder, composed of one or more suitably united sections of cast or sheet metal, as desired. This body or casing rests 55 upon a suitable bottom or base 3, supported at a suitable elevation upon legs 4 and which

is closed against the escape of ashes or other materials dropping from the grate. The top 5 of the stove may be dome shape or other suitable formation, and the stove body or casing is provided at any suitable point with an outlet 6 for the escape of the products of combustion and which is connected, in practice, with a flue or chimney of a pipe leading thereto. In accordance with my in- 60 vention, the stove is provided at its top with a fuel feed inlet 7 closed by a hinge door or lid 8, and at the bottom of the casing is pro- 65 vided an opening 9, normally closed by a door 10, through which the ashes may be re- 70 moved from the ash pit 11. The two doors are adapted to close the openings air-tight, and the door 10 is provided with draft open- 75 ings 12 controlled by a rotary damper 13 adjustable through the medium of a rotary shaft or stem 14, whereby the draft open- 80 ings may be governed, as required, accord- 85 ing to the amount of draft or air supply desired at any time in the use of the stove.

Arranged within the stove is a fire pot or 80 basket 15, which is preferably circular in form and composed of a casting or sheet metal, having at its base an annular flange or rim 16, said pot or basket being open at the top and provided in its sides with ver- 85 tically extending slots or openings 17. This basket is of less diameter than the stove body or casing so as to leave an intervening space or channel 18 of suitable width to provide for the upward circulation of air 90 and to also protect the body of the stove from direct contact with the basket or the burning fuel thereon. Provision is thus made for the upward circulation of drafts of air which not only protect the stove body 95 from an excessive degree of heat, but adapts the air taken in through the opening 9 or ventilation passages 12 to pass to the top of the stove and also through the slots or open- 100 ings 17 in the basket or fire pot, whereby the fuel and gas will be thoroughly and effi- 105 ciently oxygenated so as to secure more complete combustion and a more complete con- sumption of the fuel, giving a greater de- gree of heat and securing economy in the use of fuel.

The fire pot or basket rests upon a bottom plate or grate 19, which is provided with a central row of spaced parallel grate bars 20 and intervening slots 21 and an outer an- 110 nular row or series of radial grate bars 22 and slots 23, such construction permitting

free upward passage of air through the fuel from the ash pit and also the free downward passage of the ashes through the grate, thus allowing the grate to be shaken and the 5 ashes to be discharged with facility. The flange 16 of the basket is grooved upon its under side to form a race-way 24 for anti-friction bearing balls 25, which turn in contact with the grate 19, so that either the basket 10 or the grate may be oscillated in an arcuate path for the shaking action. In the present instance, the basket is suitably formed so as to be engaged by a handle 26 which may be inserted through the doorway 15 9 and whereby the shaking operation may, when required, be conveniently carried out.

For the purpose of supporting the basket and grate above the bottom 3 and so as to form the ash pit 11, vertical bracket members 27 are employed, each having a base 28 suitably fastened to the bottom 3 and being widened at its upper end and cut away to form a notch or receiving space 29 to receive the peripheral edge of the grate 19 and the 25 flange 16 of the basket. The lower wall of this slot is straight and horizontal and forms a shoulder 30, on which the grate rests and is supported, while the upper wall of the slot is curved correspondingly to the flange 30 29 and is extended in the form of a retaining bar or finger 31 which engages over the flange and bears against the basket and thus holds the basket against upward, downward or lateral displacement, or movement in any 35 direction, except for rotation in a horizontal plane for the shaking action. Both the basket and grate are thus firmly and securely supported in spaced relation to the casing to provide the air circulating spaces and the 40 ash pit, and so as to allow the air to pass up through the bottom and sides of the basket, whereby a thorough and efficient oxygenation of the fuel is obtained.

It will be observed that the construction 45 described does away entirely with the use of cumbersome grates and fire boxes, and that no fire-brick lining is necessary inasmuch as the body of the stove is protected by the intervening air spaces and traveling currents of air, and that no obstructions are 50 offered to the free circulation of the air or to the dislocation and downward movement of all ashes, clinkers, etc. Furthermore, it will be seen that the grate and basket are 55 simple of construction and may be applied

and removed for renewal or repairs without expert aid and by simply detaching the bolts or other fasteners connecting the brackets 27 with the base 3. It will be observed that the opening 9 in the front of the stove extends to equal degrees above and below the line of the grate, thus allowing air to pass to the ash pit below the grate and to the space 18 between the sides of the basket and the stove body, so that an efficient distribution of the air will be obtained. When the draft openings are closed, the stove will be airtight, thus preventing the unduly rapid burning of the fuel and further securing economy of consumption of the fuel material.

Having thus described my invention, I claim:

1. A stove including a body, brackets secured to and extending upwardly from the body and having recessed portions forming shoulders and overhanging projections, a grate resting upon said shoulders, a fuel basket mounted upon the grate and having openings in the sides thereof, said basket having an annular outwardly extending flange engaging the recesses of the brackets and extending under said overhanging projections, and anti-friction bearings between the grate and the flange of the basket.

2. A stove including a body having a fuel feed opening at its top and a doorway arranged adjacent to but above the bottom thereof, doors for closing said opening and doorway, the door for closing said doorway being provided with ventilation means, brackets supported by the stove body, a grate supported by said brackets in spaced relationship to the bottom and sides of the body, a fuel basket provided with openings in its sides and spaced from the wall of the body to form an intervening air space, said basket having an outwardly extending flange at its base engaged by the brackets so as to hold the basket from displacement, and anti-friction bearings between the grate and flange of the basket, the grate being arranged about midway of the height of the said doorway.

In testimony whereof I hereunto affix my signature in the presence of two witnesses.

MARK LANE MILFORD.
